UNITED STATES PATENT OFFICE.

LEWIS F. EARL, OF PHILADELPHIA, PENNSYLVANIA.

LACING-HOOK FOR SHOES, GLOVES, &c.

SPECIFICATION forming part of Letters Patent No. 602,842, dated April 26, 1898.

Application filed July 20, 1897. Serial No. 645,224. (No model.)

To all whom it may concern:

Be it known that I, LEWIS F. EARL, of Philadelphia, (Oak Lane,) county of Philadelphia, State of Pennsylvania, have invented an Improvement in Lacing-Hooks for Shoes, Gloves, &c., of which the following is a specification.

My invention has reference to lacing-hooks for shoes, gloves, &c.; and it consists of certain improvements, which are fully set forth in the following specification and shown in the accompanying drawings, which form a part thereof.

The object of my invention is to provide a suitable construction of lacing-hook which shall form a smooth or unobstructed upper surface after the lace is applied thereto, so as to prevent the possibility of the garment catching thereon.

My improved lacing-hook is especially adapted to ladies' shoes, and is designed so that the swinging of the skirts over the said hooks will not catch thereon to tear the skirt or injure the hook.

In carrying out my invention I provide a suitable eyelet or other means for attachment directly to the shoe, glove, or other garment and to which the hook proper is pivoted or loosely joined. The hook is formed of a bent piece of metal, forming, when closed upon the garment, an arch-shaped portion to confine the lace, and, further, having its free end provided with a lateral projection or tongue, forming, in effect, a hook about which the lace is drawn and retained, the lateral projection from said free end being adapted during the lacing operation to present a portion about which the lace may be wrapped so as to draw the hook into position when tightening the lace.

My invention will be better understood by reference to the accompanying drawings, in which—

Figure 1 is a perspective view showing a shoe with my lacing-hooks attached thereto and in process of receiving the lace. Fig. 2 is a perspective view of one of my improved lacing-hooks removed. Fig. 3 is a perspective view of the hook portion separated from the eyelet. Fig. 4 is a perspective view of the eyelet portion with the hook removed. Fig. 5 is a modified form of my improved lacing-hook. Fig. 6 is a modified form of the eyelet, and Figs.

7 and 8 are plan views showing a modification of my improved lacing-hook.

A is the shoe.

B are my improved lacing-hooks, and C is the lace.

While I have shown my invention as applied to a shoe, it is to be understood that it may be applied to a glove or any garment.

In applying the hook to a shoe the eyelet D is passed through a hole and upset or riveted into position as is customary in applying the ordinary lacing-hooks. The eyelet D is provided at its top with a flange E, which is stamped up into the bearings F upon each side of a flat tongue G, arranged between them and as a continuation of the flange E. The hook proper is indicated at H and is made arch-shaped. One end is provided with lateral bearing-pins h, which are adapted to fit into the bearings F of the eyelet and are held therein by the tongue G. The other or free end of the hook H is bent over and under to form a lateral tongue I, having the downwardly-extending flange i. The juncture of the parts I and H forms in effect a hook-recess, which is especially adapted to receive and hold the lace C. When the hook H is closed down upon the eyelet D, as indicated in Fig. 2, it will be seen that the portion I rests upon the flange E of the eyelet, and the projection i extends downward over the top thereof and forms no obstruction or projection upon which anything can catch.

In applying my improved lacing-hook to a shoe I prefer to set the eyelet so that the hinge on the lacing-hook is arranged at an angle to the line of the lacing-hooks or edges of the parts to be drawn together, as is very clearly seen by an examination of Fig. 1. The angle of this hinge of the lacing-hook is in opposite directions upon each side of the space between the two parts which are to be drawn together. While I prefer this angular arrangement of the hinge, nevertheless I do not confine myself to it.

In applying the lace to my improved hooks it will be seen that when the hooks are thrown open into the position shown at the upper part of the shoe of Fig. 1 the lace is drawn through the inside of the arch of the hook H, as shown at the left-hand side of Fig. 1, is then drawn downward, and then over the un-

der side of the lateral tongue I and immediately inside of the flange i, as indicated at the right-hand side of Fig. 1. Upon then drawing the lace upward it will be seen that 5 the hook H rotates about its axis F h and closes down upon the eyelet, and in so doing the part I passes over back of the lace, and the lace is left in the hook portion S, as is clearly shown in Fig. 1. The lacing-hook is 10 then retained in position by the tension put upon it by the lace itself. When the lace is loosened or removed, the hooks H drop down by gravity into the position indicated at the upper part of the shoe in Fig. 1. From this 15 it will be observed that no springs are necessary, and when the shoe is properly laced it will be practically impossible for any of the lacing-hooks to become disconnected from the lace, since the lateral tongue I extends under 20 the lace to a considerable extent and prevents it accidentally disconnecting itself from the hook H.

From the construction of my improved lacing-hook, as above described, it will be seen 25 that the entire device may be formed of stamped sheet metal, securing great rigidity with simplicity and cheapness of manufacture.

In the construction shown in Fig. 5 we have 30 the hook H loosely journaled at J to a staple K—such, for instance, as was usually employed in securing buttons upon shoes and as a substitute for the eyelet. The hook-piece, at its free end, is similar to the construction above described. In place of the 35 staple-hook K an eyelet with the bearing F', as indicated in Fig. 6, may be employed.

In the construction shown in Fig. 7 I have 40 shown the hook H as bent at its end adjacent to the hinge, but with its main portion arranged horizontally. In this case the pivot is arranged obliquely.

In the construction shown in Fig. 2 the 45 pivot-bearings are at right angles to the hook H; but in the construction shown in Figs. 7 and 8 they are arranged obliquely thereon. Otherwise the construction is substantially the same. When this modification of my improvements is applied to a shoe, the hook H 50 moves through a somewhat different angle than the hook H of the construction shown in Figs. 1 and 2.

While I prefer the construction shown I do 55 not confine myself thereto, as the details may be modified without departing from the spirit of the invention.

What I claim as new, and desire to secure by Letters Patent, is—

1. The combination with a garment, of a 60 lacing-hook consisting of a primary part secured to said garment near its edge and having an arched portion hinged or jointed at one end to the primary part on an axis arranged obliquely to the edge of the garment 65 and directed toward that part of the edge first to be acted upon when lacing the garment and having its opposite end bent over

and under to form a hook-shaped recess whereby the arched and hinged or jointed portion may fall down and away from the 70 edge of the garment under the action of gravity and when unlaced present the bent edge of the hook outward.

2. The combination of a garment, with a lacing-hook consisting of a primary part secured to said garment near its edge and having an arched portion hinged or jointed at one end to the primary part on an axis arranged obliquely to the edge of the garment 75 and having its opposite end bent over and under to form a hook-shaped recess and further provided with a lateral tongue or extension about which the lace may be wrapped to move the hook during the lacing operation.

3. As a new article of manufacture, a lacing-hook consisting of a primary part adapted to be attached to a shoe or other garment, in combination with an arched portion hinged or jointed to the primary part at one end and having its other end bent over and under to 90 form a hook-shaped recess and further provided with a lateral tongue or extension having a downwardly-projecting flange at its extreme outer edge about which tongue the lace may be wrapped to move the hook during the 95 lacing operation.

4. As an article of manufacture a lacing-hook for shoes and other garments consisting of an eyelet D having the flange E, the two bearings F stamped upward thereon, and interposed tongue G at one side of the eyelet located between the bearings, in combination with the arch-shaped hook H having one end provided with outwardly-extending journal-pins h adapted to the bearings F and held 105 therein by the interposed tongue and having its other or free end bent over and under to form the hook-shaped recess S and continued laterally as at I to form a tongue or lateral projection adapted to be received upon the 110 flange E of the eyelet.

5. As an article of manufacture a lacing-hook for shoes and other garments consisting of an eyelet D having the flange E, bearings F, and interposed tongue G, in combination 115 with the arch-shaped hook H having one end provided with journal-pins h adapted to the bearings F and having its other or free end bent over and under to form the hook-shaped recess S and continued laterally as at I to 120 form a tongue or lateral projection adapted to be received upon the flange E of the eyelet and further having its extreme end bent downward as at i to extend over the edge of the said flange E of the eyelet.

6. The combination of a shoe or garment 125 having two parts to be drawn together separated by a slit or opening the said parts being united at one end and separable toward the other and in which each part thereof is provided near its edge with a series of lacing-hooks each consisting of a primary part secured to the garment near the edge and a lacing-hook proper pivoted to the primary part

on an axis arranged obliquely to edges of the garment to be drawn together and having its free end bent under to form a hook-shaped recess and also provided with a lateral extension or tongue directed obliquely away from the opening in the garment when the hook is closed.

7. The combination of a shoe or garment having two parts formed with parallel edges adapted to be drawn together at intervals from one end toward the other and in which each part thereof is provided near its edge with a series of lacing-hooks each consisting of a primary part secured to the garment and a lacing-hook proper pivoted to the primary part on an axis arranged obliquely to the edge of the garment to be drawn together and having its free end bent under to form a hook-shaped recess and also extended to form a lateral extension or tongue directed toward the portion of the opening to be finally closed

and about which tongue the lace may be wrapped after being placed in the hook portion to draw the lacing-hook into locking position over the lace.

25

8. As a new article of manufacture, a lacing-hook consisting of a primary part furnished with means for attachment to the garment, in combination with an arched portion hinged or jointed to the primary part at one end and having its other end bent over and under to form a hook-shaped recess and further provided with a lateral tongue received directly upon the primary part to limit the movement of the said lateral projection toward the garment.

30

In testimony of which invention I hereunto set my hand.

LEWIS F. EARL.
